F. W. & R. S. VAN FLEET,
CORNER JOINT FOR SCREENS AND OTHER FRAMES.
APPLICATION FILED JAN. 30, 1917.

1,245,537.

Patented Nov. 6, 1917.

UNITED STATES PATENT OFFICE.

FREDERICK W. VAN FLEET AND RODNEY S. VAN FLEET, OF TOLEDO, OHIO.

CORNER-JOINT FOR SCREENS AND OTHER FRAMES.

1,245,537.

Specification of Letters Patent.

Patented Nov. 6, 1917.

Application filed January 30, 1917. Serial No. 145,549.

To all whom it may concern:

Be it known that we, FREDERICK W. VAN FLEET and RODNEY S. VAN FLEET, citizens of the United States, residing at Toledo, in the county of Lucas and State of Ohio, have invented a new and useful Corner-Joint for Screens and other Frames, of which the following is a specification.

This invention has reference to corner joints for screens and other frames, and its object is to provide a blind joint connection of a character permitting the shipment of the screen rails in knocked-down condition, and the ready assemblage of the screen rails into the form of a screen frame and the fitting of the frame to an opening, with great facility and with the production of an exceptionally rigid and strong frame.

For convenience of description, the invention will be referred to as a screen frame without, however, being limited in its utility to such particular kind of frame.

In accordance with the invention the rails or bars may be of like construction. Each rail is provided at one end with a looped strap of metal constituting in effect a mortise designed to receive the opposite end of a companion rail, which latter is so constructed as to both enter and embrace the mortise strap. The rail is rabbeted along one edge to receive the screen and holding bead, and along the plane of the rabbet the rail is slit longitudinally, thereby providing a tongue on one face of the rail as much narrower than the rail as is determined by the width of the rabbet. The other side of the tenon end of the rail is correspondingly slit, while the rail is cut through perpendicular to the depth of the rabbet where it joins the body of the rail to such an extent that the slit portion reaches the slit forming the tongue on the opposite face of the tenon end of the rail.

The mortise end of the rail is correspondingly slit lengthwise for a sufficient distance to receive the leg end of the mortise loop, which latter is of substantially rectangular cross-section and of a size to readily receive the tenon end of a companion rail. The mortise end of the rail is formed with a shoulder movable along the rabbet portion of the tenon end of the rail, while the mortise end is of a size to receive the entire tenon, including that portion separated from

the body of the tenon by the slit perpendicular to the plane of the face of the rabbet. The last-named slit permits the application of a wedge in the tenon to expand it tightly in the mortise, while the longitudinal slits forming the tenon are of sufficient length to permit the assemblage of the rails in a manner to adapt the frame to openings of different sizes.

The invention will be best understood from a consideration of the following detailed description, taken in connection with the accompanying drawings forming part of this specification, with the further understanding that while the drawings show a practical form of the invention, the latter is not confined to any strict conformity with the showing of the drawings, but may be changed and modified so long as such changes and modifications come within the scope of the appended claims.

In the drawings:—

Figure 1 is a perspective view of the tenon end of a rail.

Fig. 2 is a perspective view of the mortise end of a rail.

Fig. 3 is a plan view of assembled mortise and tenon ends of respective rails prior to the trimming of the assembled corner.

Fig. 4 is a view similar to Fig. 3, but showing a completed or finished corner.

Fig. 5 is a section on the line 5—5 of Fig. 3.

Fig. 6 is a section on the line 6—6 of Fig. 3.

Fig. 7 is a perspective view of a metallic mortise loop.

The screen frame of the present invention is made up of four rails 1, usually of generally rectangular cross-section, but not necessarily of any particular cross-sectional shape. The rails are customarily of such length as may be needed to produce a frame to fit a certain sized opening and provide for the fitting of the frame to other sizes of openings within such limits as may be found expedient in manufacture. Along one edge of the rail there is formed a rabbet 2, such as is customarily provided to receive wire netting 3 and a retaining bead 4. Each rail is provided with a tenon end 5 and a mortise end 6, so that one type of rail is sufficient for all four sides of the frame, such frames being customarily of rec-

tangular outline. The tenon end 5 is provided with a longitudinal slit 7 coinciding with the wire screen receiving face of the rabbet 2, the slit 7 extending from one face 5 to the other of the rail and lengthwise of the rail for such distance as may be desired, the distance being usually sufficient to permit the use of the rail for openings of various widths.

10 Entering the tenon end of the rail near the opposite face thereof, and spaced from such opposite face by a distance about equal to the depth of the rabbet 2, is another longitudinal slit 8 extending completely through 15 the rail from one edge to the other, and of a length about equal to that of the slit 7. The two slits 7 and 8 define a tenon 9, and tongues 10 and 11, respectively, on opposite sides of the tenon 9. The tongue 10 is narrower than the tongue 11 by the width of the rabbet 2. Extending transversely through the tenon 9 is another slit 12 perpendicular to the face of the rabbet 2 and dividing the tenon 9, so that it comprises a main portion 25 and a portion 9^a of less width. The slit 12 is about as long as either of the slits 7 or 8, and is designed to serve a purpose which will hereinafter appear.

Each rail has along the edge remote from 30 that provided with the rabbet 2, a central longitudinal groove or channel 13 of a width about equal to that of the tenon 9 and the slits 7 and 8 combined.

The other or mortise end 6 of each rail 35 has slits 14, 15, respectively, extending lengthwise into the end of the rail and corresponding in position to, and of less longitudinal extent than the slits 7 and 8. While the slits 7 and 8 extend entirely through the 40 rail, the slits 14 and 15 may stop short of that edge of the rail containing the groove 13. Seated in the slits 14 and 15 are the leg ends 16 of a mortise loop 17 which may be conveniently formed of sheet metal bent in- 45 termediately upon itself to provide a substantially rectangular yoke end 18 with the legs 16 substantially parallel one to the other. The mortise loop 17 is shown as having one edge of each leg 16 beveled or nar- 50 rowed, as indicated at 19, so that it may more readily fit into the slits 14 and 15 which may be in the form of saw kerfs. The legs 16 have matching perforations 20 and 21 for the passage of screws or nails, and 55 other matching perforations 22 of somewhat larger size than the first-named perforations.

That side of the mortise end 6 of the rail in which the rabbet 2 is formed has a short tongue 23 projecting lengthwise of the rail, 60 the projection of the tongue 23 corresponding to the depth of the rabbet 2 in the direction of the width of the rail, the thickness of the rabbet being only sufficient to accommodate the netting 3 and bead 4.

65 The loop 17 is applied to the end 6 of the

70 rail with the legs 16 seated in the slits 14 and 15. A pin 24 driven through the mortise end 6 of the rail and traversing the matching passages 21 serve to hold the mortise loop firmly to the mortise end of the rail, 75 while a screw 25 or other suitable fastening means entering the rail through the perforation 20 serves to further anchor the mortise loop to the rail and fixedly position it thereon.

75 When the parts are to be assembled, the the tenon 9 with its extension 9^a is introduced into the mortise loop which projects from the mortise end 6 of the rail for a sufficient distance, and this mortise loop may be 80 moved along the slits 7 and 8 to any desired distance within the lengths of these slits. In this way a frame made up of four rails may be assembled to a desired size, and then other passages 20, which are so positioned as 85 to be opposite the rabbet portion 2 of the companion rail, receive fastening devices such as screws 26 or the like, securing the loop 17 to the tenon end of the companion rail. The joint is finished by driving one or 90 more brads or nails 27 through the tongues 10 and 11, with these nails traversing the passages 22 which are made large enough to avoid liability of striking the metal of the loop 17. Before the loop 17 has been made 95 fast to the companion rail, a wedge 28 is driven into the slit 12, thus spreading the tenon members 9 and 9^a apart and tightly clamping them against the yoke end 18 of the mortise loop 17 and the end of the rail 100 from which the mortise loop projects. After the parts have been firmly secured together as in the manner described, any projecting portion of the tenon end of the rail beyond the loop end of the companion rail may be 105 cut off, and the frame is then of a size to fit the opening, or may need some little dressing with a plane, this being provided for by the grooves 13 which position the metal parts a short distance below the surface of the 110 wood at the edges of the frame.

The structure is particularly rigid, since the mortise loop may be pressed out from sheet steel and is far stronger than the wood of which the frame is customarily made, and 115 being seated in and secured to the rail provides in conjunction with the tenon end of the rail a particularly rigid and strong corner joint. If the tenon end of the rail be of considerable length it may be advisable 120 to fasten the tongues 10 and 11 by more nails than the one or two nails driven through the openings 22.

The corner joint has the reinforcing member in the form of the mortise loop embedded 125 and entirely out of sight when the screen frame is located in an opening.

What is claimed is:—

1. A joint comprising two abutting bars in angular relation, one bar having a mor- 130

- tise loop fast thereto and the other bar being provided with a tenon for entering the mortise loop and having tongues flanking the tenon and embracing the mortise loop in the assembled joint. 5
2. A joint comprising two angularly abutting bars, one having a mortise loop of less thickness than the bar carrying it and fast to and projecting from one end of the bar, 10 and the other bar having a divided tenon movable into the mortise loop and provided with tongues on opposite sides of the tenon for embracing the mortise loop, the divided tenon having its parts spaced to receive a 15 wedge for spreading the tenon within the mortise loop.
3. A joint comprising two angularly abutting bars, one having a metallic loop extending therefrom and constituting a mortise 20 loop and the other being formed with a tenon of a size to enter the mortise loop and provided with tongues on opposite sides of the tenon and in the assembled joint exterior to the mortise loop, said loop having 25 passages for fastening devices securing the loop to the bar carrying it and to the bar received by the loop.
4. A joint comprising two angularly related bars fitted together, one bar being provided with a metallic loop projecting therefrom and of less thickness than the bar and the other bar having longitudinal slits defining an intermediate tenon and flanking tongues to receive the mortise loop with the 30 tenon extending therethrough and the tongues exterior to the mortise loop in flanking relation thereto.
5. A frame bar having at one end a mortise loop of less thickness than the bar and 35 located intermediate of the thickness of the bar and extending longitudinally therefrom to provide a mortise between the yoke end of the loop and the bar, and the other end of the bar having longitudinal slits extending in the direction of the width and thickness of the bar and defining an intermediate 40 divided tenon and flanking tongues, with the tenon of a size to extend through the mortise and the tongues spaced from the 45
- tenon to receive the mortise loop between them and the tenon. 50
6. A frame bar provided at one end with a longitudinally projecting sheet metal loop having the yoke end outermost and the legs of the loop seated lengthwise into the end 55 of the bar and the other end of the bar being formed with lengthwise longitudinal slits extending through the bar to form an intermediate tenon and flanking tongues, and the tenon having a lengthwise slit dividing it 60 into two parts.
7. A frame bar provided at one end with a longitudinally projecting sheet metal loop having the yoke end outermost and the legs of the loop seated lengthwise into the end of 65 the bar, and the other end of the bar being formed with lengthwise longitudinal slits extending through the bar to form an intermediate tenon and flanking tongues, and the tenon having a lengthwise slit dividing it 70 into two parts, the mortise loop having passages therethrough for fastening devices securing it to the end of the bar from which it projects and for other fastening devices for securing the mortise loop to the tenon 75 end of a companion bar.
8. A frame including interlocking bars each provided at one end with a mortise loop projecting therefrom and located intermediate of the width of the bar in spaced 80 relation to the sides of the bar, and each bar also having a tenon end with longitudinally extended slits defining an intermediate tenon and flanking tongues with the tenon of a size to enter the mortise loop with the 85 tongues exterior thereto, and said tenon having a longitudinal slit transversely of the width of the bar to receive a wedge for spreading the tenon when located within the mortise loop. 90

In testimony, that we claim the foregoing as our own, we have hereto affixed our signatures in the presence of two witnesses.
